ABSTRACT

A powder cloud generator utilized for the development of electrostatic latent images on a receptor and having a chamber with an opening therein to receive the receptor. A selected amount of developer powder is delivered to a specific location within the chamber followed by directing a stream of gas against the powder whereby the powder particles are dispersed and a powder cloud is thereby formed in the chamber. Additionally, means may be provided for electrostatically charging the powder particles with a charge of a desired polarity.

POWDER CLOUD GENERATOR AND METHOD

BACKGROUND OF THE INVENTION

There have been developed various processes for producing images wherein initially an electrostatic latent image is formed on a suitable insulating surface, such as a film of plastic, paper, or the like which is referred to as a receptor. The latent image is then contacted with a cloud of charged powder particles. If the charged particles have the same polarity as the charges of the latent image, the powder particles will precipitate on the uncharged areas and be repelled by the latent charges. Such an image is referred to as a negative image. Alternatively, if the powder particles have a charge of an opposite polarity from the latent charge, they will, of course, be attracted to the latent image directly and thus form a positive image. Thus, one can form either a positive or a negative image, depending upon the charge of the powder particles relative to the charge of the latent image. For optimum development of such images they must be exposed to or contacted by a uniform distribution of uniformly charged developer particles, such as a homogeneous distribution of developer powder in the form of a cloud of the powder mixed with a suitable gas. Typical prior systems for producing powder clouds for developing electrostatic images are described in U. S. Pats. Nos. 2,759,450, 2,784,109 and 2,928,575.

In many of the previous systems, a powder cloud or aerosol was initially created at a location remote from the chamber or container in which the latent image was to be developed and the fine powder particles mixed with the gaseous carrier were transferred or carried by conduits or tubes to a developing zone where they contacted the receptor having the latent image thereon. Such apparatus for forming powder clouds are often referred to as powder cloud generators.

Between the powder cloud generator and the area or enclosure where the cloud contacts the latent image, the powder cloud particles preferably were electrostatically charged to have a desired polarity. In such prior art systems, the development zone normally comprised an enclosure having an opening therein where the receptor having a latent image could be placed. During transfer of the gas-powder mixture from the generator to the development zone or area by means of a tube etc., the gas of the powder cloud served additionally as a carrier. The gas-powder mixture was sprayed or delivered under pressure into the development chamber through a nozzle or the like where the charged cloud could fill the chamber and contact the receptor having a latent image thereon.

Such systems had various disadvantages. For example, the lines carrying the toner particles entrained in a pressurized gas or powder-gas mixture to the development zone had a tendency to clog. Not only did the lines often get clogged, but the nozzle, which meters the powder cloud into the development chamber, also often became clogged and prevented the flow of the aerosol or powder cloud through the system in the desired manner. This resulted in a lack of consistent or uniform results. An additional drawback of such known apparatus and methods was that relatively large volumes of gas-suspended toner powder particles under pressure were required to be handled. Further, there was often erratic triboelectric charging of the developer or toner particles, and particles in the powder

cloud delivered to the latent image on the receptor did not possess the desired uniform charge.

In other instances motor-driven whirling blades or brushes were positioned in the narrow bottom portion of a conical or other tapered wall development chamber and utilized to agitate and distribute the powder throughout the chamber. However, such apparatus did not provide as homogeneous a cloud density as most desired. Further, such apparatus is mechanically complicated by the presence of a large motor and associated means for rotating the brush or blades. Additionally, rotating parts tend to wear, which requires periodic replacement thereof including disassembly of the apparatus.

SUMMARY OF THE INVENTION

The present invention overcomes the disadvantages of the prior art and provides improved control of development of the latent image and resolution thereof, increased economy of toner usage, and simpler and more reliable apparatus. Other objects and features will be in part apparent and in part pointed out hereinafter.

Briefly, the present invention includes an enclosed development chamber having an opening therein in which a receptor element having a latent electrostatic charge image is disposed for developing. Means is provided for delivering a selected amount of a developer powder within the chamber which includes means for receiving a selected amount of powder to rest thereon. A gas inlet is connected to the chamber for introducing a gas thereto, and it is positioned to deliver the gas so as to force the powder from the receiving means and distribute it as a cloud throughout the chamber.

More specifically, adjacent the gas inlet there is a platform constituting the receiving means and on which is deposited a selected amount of the powder utilized for a development. The gas is directed toward the deposited amount of this toner powder dispersing it within the chamber in the form of a cloud. Preferably between the body of deposited toner and the main chamber portion there is a grounded fine metal mesh screen. Above the body of toner resting on the platform, there is located a d.c. corona discharge device. In this manner, the toner particles are all charged uniformly and of the desired polarity as they are picked up by the incoming gas and directed into the chamber in the form of a charged powder cloud.

BRIEF DESCRIPTION OF THE DRAWINGS

FIG. 1 is a cross section, with certain internal parts shown in elevation and other elements shown schematically, of powder cloud apparatus of this invention; and

FIG. 2 is a section on line 2-2 of FIG. 1.

Corresponding reference characters indicate corresponding parts throughout the several views of the drawings.

DESCRIPTION OF A PREFERRED EMBODIMENT

Turning now to the drawings, indicated generally at 11 is powder cloud apparatus of this invention which comprises a generally enclosed preferably electrically grounded box or enclosure 13 of aluminum or any other suitable electrically conductive material which will not sustain electrostatic charges. Box 13 has an opening 15 in its top surface 17. An image receptor 19 comprising a substrate of an insulative material having a latent electrostatic image thereon is disposed or

mounted over opening 15. In accordance with the present invention, this apparatus is generally useful for the development of any charged latent image on substrate 19. This substrate may be a xerographic plate having a photoconductive insulating material overlying a conductive backing member. The photoconductive insulating layer has an electrostatic charge formed thereon as a latent image corresponding to the light pattern to which it is exposed. The insulative layer having this latent image is then placed over the opening 15 so that the latent image is exposed to chamber 21 defined by the interior of box 13, and the image is then developed. Alternatively, image receptor 19 may be a layer of insulating material such as a plastic sheet or the like which has a latent charge thereon formed as a result of an ionographic process such as that described by K. H. Reiss in Z. Angew. Physik, Vol. 19, p. 1 (1965). Once again, the surface of insulative receptor layer 19 having a latent image is exposed to the chamber 21 through the opening 15. Thus, it will be understood that image receptor 19 may comprise virtually any layer which as a result of any process has an electrostatic latent image formed thereon and which image is susceptible of development.

Secured to a side wall 23 of chamber 13 and extending inwardly to the chamber 21 is a flat, generally horizontal platform 25. Platform 25 is enclosed by side walls 27 and a top wall 29 forming a small compartment surrounding the platform 25, with platform 25 forming the compartment bottom and a small portion of chamber wall 23 forming the rear wall thereof. Projecting downwardly through the compartment's top wall 29 is an inlet tube 31 which passes through top surface 17 of the main housing or chamber 13. Inlet tube 31 provides access to deliver a selected amount of powder particles 33 into chamber 21 to come to rest on platform 25. The amount of powder particles 33 deposited on platform 25 will be determined by the geometry of the chamber 21 and the desired density of the powder cloud to be formed therein. The amount of powder 33 may be manually measured and fed into tube 31. Alternatively, conventional automatic measuring and feeding means may be readily provided to feed the desired amount of the powder for each cycle of development, or for each receptor 19 placed on the device.

The types of powder material utilizable in the present invention are well known in the art. Typical powder materials include charcoal, carbon black and various carbonaceous type pigments. Additionally, finely divided material having pigments added thereto can be used such as finely-divided resins containing pigments or dyes. The utilization of resins is desirable where the formed image is to be ultimately fused by heat or other means. The particle size of the powder material is relatively small in order to maintain a good resolution of the developed image. For example, particles having average diameters on the order of one to ten microns are normally utilized. It should be emphasized that the powder per se, frequently referred to as toner, does not form part of this invention and any of the powders well known in the art can be utilized and are herein contemplated. The density of the developed image is controlled in part by the amount of powder used. The volume of the powder used for good development density is dependent on the particular chamber dimensions.

A gas inlet tube 35 extends through chamber wall 23 and terminates in the small compartment with its end

37 disposed adjacent the platform 25 on which rests the body of powder 33. The relative elevations of the outlet end 37 of gas inlet tube 35 and platform 25 above bottom wall 36 of the chamber are such that a desired deposition of powder fines will occur on the receptor 19. In powder cloud development, the objective is to cause large powder particles to fall away from the image receptor, with only fines being carried upward to the latent image. Placing the platform 25 too close to image receptor 19 can cause impingement of large powder particles on the receptor. If the platform 25 is too far from the image receptor, then the latent image will be underdeveloped. However, while there is some latitude in the placement of the gas inlet so as to achieve desirable results, the most desirable location of the inlet tube is easily and readily determined.

The inner end 37 of the tube 35, which is preferably flattened slightly to improve cloud formation, is disposed adjacent the powder particles 33 to deliver the incoming gas so that it will disperse the powder resting on the platform 25, blowing it into chamber 21. Preferably, a fine wire mesh screen 39 is provided to break up agglomerations in the powder as it enters the chamber volume 21 when the gas blows the powder off the platform. The screen 39, which is preferably grounded, can be made of stainless steel, copper or any other metallic conductor. Typical mesh size for screen 39 will range from 150 to 250 mesh in order to properly break up such agglomerations in the powder mass 33. Clogging of the screen can occur if damp powder or a gas with a high moisture content is used. Thus, it is desirable that the screen be removable from the device for cleaning, if required.

The gas entering through the line 35 can be air or any other suitable dry carrier gas. Obviously, air is the most practical and least expensive carrier gas. The gas is admitted under a preset pressure, the duration of gas inlet being controlled by a timer actuated valve 38. A typical range of flow rates of the gaseous material utilized can be from 2.3 to 5.3 cubic feet per minute. The gas flow rate is controlled by the gas pressure, the length of tube 35, the tube's bore diameter and temperature. To obtain the above typical flow rates, pressure settings range from 3 to 10 psi. Typically, a gas pressure of 4 psi maintained for 10 seconds provided good results. Image density appears to be relatively independent of the gas inlet pressure and duration once minimums have been established to provide complete overall image development.

Box or housing 13 preferably has an enlarged opening 41 at the bottom thereof. A filter 45 of spun glass or the like covers the opening 41 while a baffle element 46 is spatially disposed above the filter within the chamber. This allows the gas to leave the chamber while filtering out the powder particles. In other words, during the development, the gas is continuously being fed into the chamber and flowing therethrough and out through the filter 45 while maintaining a constant cloud of powder particles therein. This, of course, permits a continuous turbulence within the chamber 21 to maintain a consistent density powder cloud throughout, providing for an enhanced image. This results in development with good reproducibility or repeatability of performance for each separate development of successive imaging receptors 19.

Partially disposed in the inlet tube 31 and extending downwardly to a point just above the powder 33 is an

electrode 47 which is insulatively mounted in the tube 31 and connected to a suitable high voltage source 49, e.g., up to 10 kv or more. The other terminal of voltage source 49 is preferably grounded, but it is to be understood the expression "grounded" as used herein encompasses merely connecting the screen and platform to the voltage source terminal of polarity opposite to that terminal which is connected to electrode 47, and does not necessarily mean an actual earth ground.

The electrode 47 provides the desired corona discharge into the powder cloud formed when the gas from tube 35 causes the powder to be dispersed. The corona discharge is thus formed between a sharp end 51 of the electrode 47 and the grounded wire mesh screen 39. The end of the electrode is located just above the top of the body of powder 33 so that the incoming gas can serve to continuously clean it. Since the powder particles must pass through screen 39, they in turn inherently are moved through the corona discharge and will be charged according to the desired polarity as determined by the polarity of the discharge. The applied high voltage to the electrode 47 as well as the discharge current are limited to prevent actual arcing. A corona "glow" is generated at the sharp end of the electrode, this corona discharge ionizes the air surrounding the powder, and thereby effectively charges the suspended toner or powder particles. The screen provides a convenient ground while simultaneously serving to break up powder agglomerates. The platform 25 (formed of brass or other material which has an electrically conductive surface connected to screen 39 and the grounded terminal of voltage source 49) preferably has divergent walls 48 positioned on opposite sides of powder body 33 as seen in FIG. 2. These walls serve to diffuse and direct the powder cloud over a maximum area of the screen 39. The screen is preferably of a semicircular shape to aid in cloud diffusion by presenting a large area of screen which, in combination with the divergent walls of the platform, spreads the cloud out to the full width of the receptor.

Powder feed tube 31 preferably has a removable cap 53 which serves to seal the tube after a charge of powder has been admitted or introduced into the chamber. Alternatively, of course, a valve can be utilized in place of cap 53 particularly where an automatic feed means is provided. Means thus should be preferably provided for closing the tube 31 at the top thereof so that during the generation of the powder cloud the cloud cannot escape through the tube and affect the performance of the apparatus. Such an automatic continuous powder feed having a belt carrying individual capsules of a predetermined amount of powder may be provided so that as the belt is advanced new capsules successively are brought into alignment with the gas inlet. Each capsule would then be opened just prior to beginning gas flow for development of a particular image. This belt would

thus, in effect, replace the platform since the powder would be resting on the belt surface prior to dispersion.

In using the above-described apparatus to practice the methods of this invention, a measured amount of powder or toner is delivered to the platform prior to development of each latent image and the powder cloud produced by directing the stream of gas at the powder body is blown directly into chamber 21 with the toner particles uniformly charged at the desired polarity as they pass through the corona discharge. At no time is a mixture of gas and powder moved through a tube or restricted conduit. The powder cloud herein is actually created within the confines of the development chamber. Thus, there is no possibility of clogging of tubes or nozzles and a consistent homogeneous powder cloud is formed. By convenient adjustment of the amount of powder selected, gas pressure and the duration of gas flow, excellent control of development of the latent image and good resolution thereof are obtained with good toner economy.

In view of the above, it will be seen that the several objects of the invention are achieved and other advantageous results attained.

As various changes could be made in the above apparatus and methods without departing from the scope of the invention, it is intended that all matter contained in the above description or shown in the accompanying drawings shall be interpreted as illustrative and not in a limiting sense.

I claim:

1. Powder cloud apparatus comprising:
an enclosed chamber having an opening therein in which an image receptor can be disposed;
means for delivering a selected amount of a developer powder within said chamber;
a generally horizontal platform disposed in said chamber for receiving said powder and allowing the powder to rest thereon;
an electrically-grounded screen disposed adjacent said platform to diffuse the powder as it is blown therefrom by gas from inlet means;
a corona discharge electrode disposed adjacently above said platform whereby a corona discharge can be generated between said screen and said electrode; and
gas inlet means connected to said chamber for introducing a gas burst thereto, this inlet means being positioned to deliver the gas so as to propel the powder from its receiving means and disperse and distribute it as a cloud across the chamber.
2. Powder cloud apparatus of claim 1 wherein said means for admitting the powder includes a tube, said electrode being mounted within said tube.
